US00D724277S

(12) **United States Design Patent**
Avalos Sartorio et al.

(10) **Patent No.:** **US D724,277 S**
(45) **Date of Patent:** **** Mar. 10, 2015**

(54) **FOOD PLATE FOR PETS**

(71) Applicants: **Miguel José Avalos Sartorio, Zapata (MX); Carlos José Avalos Sartorio, Zapata (MX)**

(72) Inventors: **Miguel José Avalos Sartorio, Zapata (MX); Carlos José Avalos Sartorio, Zapata (MX)**

(**) Term: **14 Years**

(21) Appl. No.: **29/499,850**

(22) Filed: **Aug. 19, 2014**

(30) **Foreign Application Priority Data**

Mar. 12, 2014 (MX) MX/f/2014/000837

(51) **LOC (10) Cl.** **30-03**

(52) **U.S. Cl.**

USPC **D30/130**

(58) **Field of Classification Search**

USPC D30/121, 129-132; 119/51.5, 61.5, 119/51.54; D1/124; D7/553.8, 555, 556; D9/609, 643
